FRANK E. BRUCE, CHARLES A. BRUCE, AND JAMES B. HAYGOOD, OF MEMPHIS, TENNESSEE, ASSIGNEES TO E. L. BRUCE COMPANY, OF MEMPHIS, TENNESSEE, A CORPORATION OF DELAWARE

WOOD-BLOCK FLOORING

Application filed April 4, 1928. Serial No. 267,456.

Our invention relates to wood block flooring and one of the objects of the invention is to provide what is known as a wing block and which is used when laying rectangular blocks diagonally of the wall line of the room. The diagonal laying of block flooring is a preferred method of laying for many reasons, among which is the fact that when so laid, the floor shows up to much better advantage, one block appearing dark and the adjacent block appearing light, by reflected light.

When the blocks are laid in diagonal fashion, then, along the edges of the room, it is necessary to provide a filling-in block of other shape than rectangular. This is usually done now by mitreing the pieces on the job, but this is an expensive operation. When these pieces are made in the factory, difficulty is experienced in manufacturing them accurately because one of the pieces is a very small piece. Furthermore, such pieces are difficult to transport satisfactorily.

Referring to the drawing for a more complete disclosure of the invention:

Fig. 1 is a plan view of a section of flooring showing the wings blocks in position;

Fig. 2 is a bottom plan view of one of the blocks; and

Figs. 3 and 4 are side elevations of the block shown in Fig. 2.

The rectangular blocks 2 are composed of a plurality of pieces 3 of strip flooring which are secured together in any suitable manner to make a unitary block. The grain of the pieces 3 runs lengthwise so that the grain of each block 2 is at right angles to the grain of the adjacent block. In laying block flooring diagonally of the room, it is preferred to start from a central point of the room and build the floor outwardly toward the sides of the room. When the last of the square blocks 2 have been laid, then we lay our wing blocks 4 in position.

The wing blocks may be laid with one edge directly in contact with the wall 14 of the room, or the customary line borders or strips of flooring 5 may be inserted between the wing blocks and the wall.

The wing block as shown comprises a

plurality of pieces of strip flooring 6 united along their edges by tongue and groove connections 7. The strips are securely held together in any suitable manner, that shown being a metal spline 8 forced into locking engagement with the sides of the transverse grooves 9, all as fully disclosed and claimed in the copending application of Charles W. Allen, Serial No. 198,085, filed June 11, 1927. The diagonal edges 10 of the wing block will be of the same length as the sides 15 of the rectangular block 2 that they are in contact with. The width of the wing block will accordingly be the distance between the ends of the diagonal edges 10. It will be clear that the length of the sides 11 may vary as the necessities of the situation vary and may be equal or unequal in length, depending in turn on whether or not the sides of the room are true.

In the wing block shown, grooves 16 are provided on all sides for the reception of either an integral adjacent tongue or of a slip tongue for holding the wing block in position. The wing block may be made of pieces of equal width as shown in Fig. 1, but in such a case the strips would have to be made specially and the stock sizes of flooring strips could not be utilized. The standard widths for oak flooring strips are 1 1/2, 2 and 2 1/4 inches wide for 3/8ths, 1/2 and 1 1/8ths inch thickness.

As shown in Fig. 2, there are used three pieces 12 of 2 1/2 inch and 2 pieces 13 of 1 1/2 inch flooring, it being necessary, in this particular case, in order to fit the wing block between the 6 3/4 inch square blocks 2, to knock off slightly the two outside edges of the two outside pieces of flooring 12. An analogous situation exists with 9 inch square blocks, the wing block being built up by using four pieces of 2 1/4 inch stock and two pieces of 2 inch stock.

While we have disclosed a construction for holding the wing blocks in position and in which there are grooves on all sides, of the wing block, it will be understood that other means for abutting and holding the blocks in position may be employed than that shown. In using strips of stock floor-

ing, having a groove and tongue on opposite edges of the strip, it will be convenient at times to have one of the edges 11 of the block grooved and the other edge 11 provided with a tongue.

5. When the wing blocks are made of strips of equal width, as shown in Fig. 1, the pieces can be so joined that the joints in the square blocks will correspond with those in the wing blocks, when these joints contact.

10. It will be clear from the above description that the length of the diagonal sides 10 of the wing block will be determined by the length of the sides of the rectangular blocks; that the side of the wing block facing the wall will be determined, in the main, also by the length of the sides of the rectangular blocks; but that the length of the sides 11 of the wing block do not need 15 to be definitely fixed.

20. We are aware that our invention may be embodied in other specific forms without departing from the spirit or essential attributes thereof and we therefore desire the 25 present embodiment to be considered in all respects, as illustrative and not restrictive, reference being had to the appended claims rather than to the foregoing description, to indicate the scope of the invention.

30. Having thus described our invention, which we consider as new and useful and desire to secure by Letters Patent, is:

1. A floor made of blocks laid diagonally 35 of the room, a continuous series of wing blocks fitting between the entire length of the wall of the room and the first named blocks, the said wing blocks being polygonal in outline and having more than three sides 40 and being composed of strips of wood fastened together and lying substantially perpendicular to the wall of the room.

2. A floor made of blocks laid diagonally of the room, a wing block fitting between 45 the wall of the room and the first named blocks, the said wing block composed of strips of wood fastened together and lying substantially perpendicular to the wall of the room and means on the wing block engaging the first named blocks for abutting 50 and holding the wing block in position in the floor.

3. A wing block composed of a plurality 55 of strips of wood, means for holding the strips of wood in assembled relationship, the said block being polygonal in outline and comprising a base with respect to which the strips are substantially perpendicular and diagonal sides which are at an acute 60 angle to the base and means on the diagonal sides for abutting and holding the wing block in position in the floor.

4. A wing block composed of a plurality 65 of strips of wood, means for holding the strips of wood in assembled relationship,

the said block being polygonal in outline and comprising a base with respect to which the strips are substantially perpendicular and diagonal sides which are at an acute angle to the base, the said diagonal sides being 70 perpendicular to each other and means on the diagonal sides for abutting and holding the wing block in position in the floor.

5. A wing block composed of a plurality 75 of strips of wood, means for holding the strips of wood in assembled relationship, the said block being polygonal in outline and comprising a base with respect to which the strips are substantially perpendicular, diagonal sides which are at an acute angle to the base and longitudinal sides which are 80 perpendicular to the base.

6. A wing block composed of a plurality 85 of strips of wood, means for holding the strips of wood in assembled relationship, the said block being polygonal in outline and having five sides.

7. A wing block composed of a plurality 90 of strips of wood, means for holding the strips of wood in assembled relationship, the said block being polygonal in outline and having five sides and comprising a base with respect to which the strips are substantially perpendicular.

8. A wing block composed of a plurality 95 of strips of wood, means for holding the strips of wood in assembled relationship, the said block being polygonal in outline and comprising a base with respect to which the strips are substantially perpendicular, diagonal sides which are at an acute angle to the base and longitudinal sides which are 100 perpendicular to the base, the said diagonal sides and the base being grooved.

9. A wing block composed of a plurality 105 of strips of wood, means for holding the strips of wood in assembled relationship, the said block being polygonal in outline and comprising a base with respect to which the strips are substantially perpendicular, diagonal sides which are at an acute angle to the base and longitudinal sides which are 110 perpendicular to the base, the said diagonal sides, the base and at least one of the longitudinal edges being grooved.

10. A wing block composed of a plurality 115 of strips of wood united along their longitudinal edges by tongue and groove joints, means for holding the strips of wood in assembled relationship, the said block being 120 polygonal in outline and comprising a base and diagonal sides, the longitudinal edges of all the strips being at an angle to the diagonal sides and means on the diagonal sides for abutting and holding the wing 125 block in position in the floor.

11. A wing block composed of a plurality 130 of strips of wood, means for holding the strips of wood in assembled relationship, the said block being polygonal in outline and

- comprising a base and diagonal sides, the longitudinal edges of all the strips being at an angle to the diagonal sides and means on the diagonal sides for abutting and holding the wing block in position in the floor.
- 5 12. A wing block composed of a plurality of strips of wood united along their edges by tongue and groove joints, means for holding the strips of wood in assembled relationship, the said blocks being polygonal in outline and comprising a base and diagonal sides, and means on the diagonal sides for abutting and holding the wing block in position in a floor.
- 10 15. In testimony whereof we affix our signatures.
